UNITED STATES PATENT OFFICE

LAWRENCE JANECKO, OF HEGEWISCH, ILLINOIS

WINDOW

Application filed September 22, 1928. Serial No. 307,612.

The present invention relates to windows, and has for its primary object the provision of a storm window which may be simple in construction and which could be easily fitted within the window frame.

Another object of the present invention is the provision of a storm window provided with suitable locking means operable from within the dwelling.

10 A still further object of the present invention is the provision of a storm window which may be made in two sections.

With the above general objects in view and others that will appear as the nature of the 15 invention is better understood the same consists in the novel construction, combination and arrangement of parts hereinafter more fully described, illustrated in the accompanying drawings and pointed out in the 20 appended claim.

In the drawings forming a part of this application, and in which like designating characters refer to corresponding parts throughout the several views,

25 Fig. 1 is a perspective view of the window frame and the storm window, constituting the present invention, partly open;

Fig. 2 is an enlarged view, partly in section and partly in elevation of the hinge used 30 in connection with the present invention;

Fig. 3 is an enlarged cross-sectional view through a sash bar and locking means used in connection with the window;

35 Fig. 4 is an enlarged perspective view of a plate and pin used in connection with the window;

Fig. 5 is an enlarged cross-sectional view through the lower sash bar of the lower portion of the window showing another latching 40 means used in connection with the window;

Fig. 6 is an enlarged elevational view of the hinge used for the upper section of the window; and

45 Fig. 7 is a perspective elevational view of a modified form of the invention.

Referring in detail to the present invention there is shown a window frame 10 with the usual inner window generally indicated by 11. The storm window constituting the 50 present invention, adapted to be positioned

outwardly of the inner window 11, consists of upper and lower sections, generally indicated by 12 and 13, respectively.

Affixed to the upper ends of the upright portions of the window frame 10 and at the 55 inner faces thereof by screws passing through apertures 14, is substantially rectangular plate 15. Said plate 15 at the outer edge has an outwardly and upwardly projecting hook 16 affecting, in conjunction with a portion of the outer edge of said plate 15, a recess 17 for the purpose hereinafter described. The outer edge of said plate 15 while the same is in an operative position upon frame 10, remains flush with the outer 60 face of said frame 10 so that hook 16 alone projects outwardly of said frame 10, as is clearly seen on Figs. 1 and 7.

The upper section 12 of the storm window at its two upper corners carries plates 18, 70 having at its upper ends laterally projecting pins or bolts 19. Said plates 18 are affixed to said upper portion 12 of the window by means of screws 20 passing through apertures 21 made in said plates 18. Said bolts 19 are receivable within said recess 17 of plate 15. Thus, plate 15, hook 16, plates 18 and bolts 19 constitute hinges by means of which said upper sections of the window are suspended upon and within frame 10. 75

The lower horizontal sash bar of the upper section 12 of the window and the upper horizontal sash bar of the lower section 13 of the window are suitable dove-tailed as at 22 making said sash bars interfit when the two 80 sections of the window are closed for the purpose of preventing rain or dust entering the dwelling.

The two sections 12 and 13 of the window are hinged to each other by means of two or more hinges illustrated on Fig. 2. Each of said hinges includes plate 23 which is affixed by screws to the horizontal upper sash bar of the lower section 13 of the window, said plate 23 being provided with a pair of openings 24 permitting the insertion of the screws. Integrally formed with at the upper end of said plate 23 is a loop 25. The other half of the hinge includes plate 26 provided with a plurality of openings 27 for insertion of 100

screws by means of which said plate 26 may be affixed to the inner face of the lower horizontal sash bar of the upper section 12 of the window. Integrally formed with said plate 5 26 at its lower end is a cylindrical loop 28 and which registers with loop 25 of plate 23 when the two plates 23 and 26 are in the relative operative position upon the two sections of the window, it being understood that said 10 cylindrical loops 25 and 28 are substantially on a line with meeting edges of the horizontal sash bars of the upper and lower sections of the window.

Cooperating with said cylindrical loops 25 15 and 28 is a bolt including its enlarged end portion 29 and reduced portion 30 and head 31. Interposed between said enlarged portion 29 and head 31 and encompassing said reduced portion 30 of said bolt is a coil spring 20 32, by means of which said enlarged portion 29 of said bolt is urged within cylindrical loop 25 of plate 23, it being understood that the end of spring 32 adjacent the outer end of cylindrical loop 28 and head 31 is either 25 soldered to said outer end of said cylindrical loop 28 or in any other suitable manner anchored thereto.

As is apparent from the hereinabove description of the construction of the hinge illustrated on Fig. 2, on manually pulling at 30 head 31 bolt 29 will become withdrawn from the cylindrical loop 25 and thus the two sections of the hinge will become disconnected thereby causing the disconnection of the upper and lower sections of the window.

The window is further provided with latches which are generally indicated by numeral 33 upon Figs. 1 and 7 and one of which is shown in detail on Fig. 3. Each of said 40 latches includes a metallic pipe 34 which remains within a bore made in the respective upright sash bars of either lower or upper sections of the window wherever said latches are situated, having reference to the preferred 45 form of the invention shown on Fig. 1 and the modified form thereof illustrated in Fig. 7. Said pipe at the end adjacent the window pane 35 has an inward flange 36 and at its outer end an outer flange 37 which is embedded 50 in the sash bar. Positioned within said pipe 34 is a bolt including its enlarged outer end 38 corresponding in diameter to the diameter of pipe 34, and a reduced portion 39 which carries coil spring 40 which is interposed 55 between flange 36 and said enlarged portion 38 of said bolt. Said latch further includes outwardly projecting head 41 which carries ring 42 by means of which said latch bolt may be manually operated. In alignment 60 with pipe 34 when the sash bar of a given section of the window is in closed position within the frame 10, is a bore 43 wherein the outer end of said enlarged end 38 of said bolt is receivable. It will be therefore seen 65 that normally when the storm window is in

closed position the same will become locked to the frame 10 by virtue of said bolt 38. In order to open the storm window said bolt will become withdrawn from bore 43 on manually pulling at the ring 42, it being understood 70 that spring 40 urges bolt 38 outwardly of the sash bar and within bore 43 when the storm window is in an operative position with the frame 10. The preferred form of the invention illustrated on Fig. 1 has only two of the 75 latches 33 shown in detail on Fig. 3, each of them being positioned upon the vertical sash bars substantially at the central portions thereof of the lower section 13 of the storm window.

Affixed to and countersunk in each of the outer faces of the vertical sash bars of the lower section 13 of the window and the lower ends thereof is plate 44 having apertures 45 through which the affixing screws pass. Integrally formed with and outwardly projecting from the lower end of each of said plates 44 is a bolt or pin 46 which is receivable within groove 47 made in the vertical portions of the window frame 10 and in the inner faces 90 thereof, as seen on Fig. 1.

At the inner face of the horizontal lower sash bar of the lower section 13 of the storm window is plate 48 affixed by screws 49. Projecting from said plate 48 is a bifurcated 95 stud 50 to which arm 51 is hingedly connected by means of bolt 52. A leave spring 53, mounted by one of its ends in plate 48 and bearing against the upper edge of arm 53, urges said arm 53 downwardly. Said arm 100 53 at its outer end is provided with a hook 54 which is adapted to engage lug 55 which is upwardly projecting from plate 56, and which is affixed to the window sill 57 by means of screw 58.

Said locking means last hereinabove described and shown in detail on Fig. 5, hold the lower section 13 of the storm window in locked engagement with the window frame in addition to latches 33. Same locking means for the lower section 13 of the storm window may be provided for the lower section in the modified form of the invention shown on Fig. 7.

Said modified form of the device illustrated on Fig. 7 differs from the preferred form illustrated on Fig. 1, in that the two sections 12 and 13 of the window are not hinged although they are dove-tailed at the horizontal meeting sash bars as at 22. Furthermore the upper sections 12 of the modified form of the storm window has latches 33 at the lower ends of vertical sash bars.

From the hereinabove description it will be apparent that the two sections 12 and 13 of the preferred form of the invention open outwardly and shift angularly upon their hinges 23—26. To maintain said sections in open position as shown on Fig. 1, a piece of block or some other object may be placed be- 130

low the horizontal lower sash bar of the lower section 13 of the window. Since pins 46 at all times remain within grooves 47 the lower end of the lower section 13 of the window is adapted to move lengthwise of said grooves 47 of the upright bars of frame 10, while the remaining portions of said lower section is adapted to make angular motions with respect to said frame and with respect to the upper section 12 of the window.

While there is described herein a preferred embodiment of the present invention, it is nevertheless to be understood that minor changes may be made therein without departing from the spirit and scope of the invention as claimed.

What I claim as new is:

In a storm window construction of the type having a frame and a pair of superposed sashes hingedly connected at their meeting edges and in their closed position seating within the window frame substantially flush with the outside surface of said frame to bring the upper rail of the upper sash beneath and against the window frame, the bottom of the lower sash pivotally and slidably connected with the window frame, hook connections formed to extend out from the window frame and each having a vertical slot 20 in the outside end to receive pins carried by each end of the upper sash thereby connecting the top of the upper sash with the window frame to permit disengagement of the upper sash from the frame by movement of 25 the sash outwardly substantially clear of the frame and upwardly when cleared in a substantially vertical direction only, said hook connections normally maintained in engagement solely by the weight of the sash and by 30 engagement of the upper rail of the upper sash with the window frame to retain the sash on the frame.

In testimony whereof I affix my signature.
LAWRENCE JANECKO.
